LEO F. BOEDIGHEIMER, OF PETERSBURG, NORTH DAKOTA.

OIL CAN.

Application filed August 30, 1926. Serial No. 132,557.

This invention relates to oil cans, and contemplates a structure which can be very quickly and conveniently filled without soiling the hands, and from which can the oil is forced by a spring pressed plunger, so that the can can be used when held in any position, the flow of the oil from the can being controlled by a manually actuated valve.

The nature and advantages of the invention will be better understood when the following detail description is read in connection with the accompanying drawing, the invention residing in the construction, combination and arrangement of parts as claimed.

15 In the drawing forming part of this application like numerals of reference indicate similar parts in the several views and wherein—

Figure 1 is a vertical sectional view 20 through the can forming the subject matter of the present invention.

Figure 2 is a top plan view.

Figure 3 is a bottom plan view.

Figure 4 is a sectional view taken through 25 the can directly above the plunger.

Referring to the drawing in detail 10 indicates the body of the can which is provided with the usual spout 11, and a handle 12. The bottom of the can is provided with a 30 centrally located filling opening which is normally closed by a cap 13, the can being filled through this opening subsequent to the removal of the cap, in a manner to be presently described.

35 Arranged to operate within the can is a plunger 14 which is provided with a gasket 15 of any suitable character, while the plunger is also provided with a central opening 16 adapted to be controlled by a check valve 17, the latter operating within a gauge including cross rods or bars 18 and 19 as clearly illustrated in Figure 4. Interposed between the bottom of the can 10 and the plunger 14 is a coil spring 20 which tends to force the 40 plunger upwardly within the can, the plunger being moved downwardly against the tension of this spring by means of a rod 21 which slides through a packing nut 22 as clearly shown in Figure 1. This rod 21 is 45 arranged in parallelism with the spout 11 and is provided with a knob or head 23 so that the rod can be conveniently actuated when desired. The bottom of the can is also provided with a vent opening 24 normally 50 closed by a flap valve 25.

Arranged within the spout 11 and at the lower end thereof is a partition 26 having an opening 27 through which oil from the can passes into the spout, and this opening is controlled by a normally seated spring 60 pressed valve 28, the spring for the valve being indicated at 29. The valve includes a stem 30 which projects laterally from the spout 11, and which stem when pressed upon, unseats the valve 28 to allow the oil to flow 65 from the can as will be readily understood. As hereinabove stated, the oil is forced from the can by the spring pressed plunger 14, so that the can can be used when held in any position, the flow of oil being controlled by 70 the valve 28.

In practice, when it is desired to fill the can with oil, the cap 13 is removed from the filling opening above mentioned, and a filling spout (not shown) threaded into the filling opening in the bottom of the can. This spout is then lowered into a source of supply, and the plunger 14 lowered against the tension of the spring 20, by means of the rod 21. The rod 21 is then released and the 80 spring 30 functions to elevate the plunger 14, during which time the oil is sucked from the source of supply into the can 10, the flap valve 25 being closed during this operation. The cap 13 is then placed upon the bottom 85 of the can to close the filling opening, and the plunger 14 again lowered into the body of oil contained in the can 10. During this movement of the plunger the check valve 17 is opened, thereby allowing the oil to pass 90 through the opening 16, from the under side to the upper side of the plunger. After all oil has passed through the plunger 16 to occupy the upper portion of the can 10, the plunger 14 is influenced by the spring 20, to 95 force the oil from the can through the spout 11, independently of what position the can may be held in. As above stated, the flow of the oil through the spout is controlled by the valve 28 which can be conveniently opened 100 by the thumb of the user, and automatically closed by the spring 29.

While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

An oil can including a spout, a valve controlling communication between the spout and can, said can having a filling opening in the bottom thereof, a cap normally closing said opening, a plunger operable within the can and having a sealing fit within the body to suck oil into the can through the filling opening when moved in one direction, a spring 10 influencing said plunger in one direction, a

rod connected with the plunger for depressing the latter against the tension of said spring, said plunger having a central opening, a check valve reposing upon said plunger and normally closing said opening, and adapted to be opened when the plunger is depressed to allow the oil admitted to the can to pass into the upper portion of the latter. 15

In testimony whereof I affix my signature.

PHILIZA H. FONTAINE.
